(57) **CLAIM**

The ornamental design for a cover for syringe pump rack and/or infusion pump rack, as shown and described.

DESCRIPTION

The patent or application file contains at least one drawing executed in color. Copies of this patent or patent application publication with color drawing(s) will be provided by the Office upon request and payment of the necessary fee.

FIG. 1 is a left perspective view of a cover for syringe pump rack and/or infusion pump rack;
FIG. 2 is a right perspective view thereof;
FIG. 3 is a front view thereof;
FIG. 4 is a rear view thereof;
FIG. 5 is a left side view thereof;
FIG. 6 is a right side view thereof;
FIG. 7 is a top view thereof; and,
FIG. 8 is a bottom view thereof.

The de-emphasized light gray area in FIG. 8 depicts portions of the cover for syringe pump rack and/or infusion pump rack that form no part of the claimed design.
